INVENTOR.
FRED HARRINGTON
BY *A. B. Donnan*
ATTORNEY

UNITED STATES PATENT OFFICE.

FRED HARRINGTON, OF SAN DIEGO, CALIFORNIA.

ACCELERATOR EXTENSION-PEDAL FOR AUTOMOBILES.

1,383,114.

Specification of Letters Patent. Patented June 28, 1921.

Application filed February 24, 1920. Serial No. 360,734.

To all whom it may concern:

Be it known that I, FRED HARRINGTON, a citizen of the United States, residing at San Diego, in the county of San Diego and State 5 of California, have invented a certain new and useful Accelerator Extension-Pedal for Automobiles, of which the following is a specification.

My invention relates to an accelerator extension pedal for automobiles and the objects of my invention are:

First, to provide a device of this class which is applicable for use in connection with the various makes of accelerator pedals 15 now in use; second, to provide a device of this class which is supported in such a manner that it may be readily applied in connection with the various makes and angles of footboards now in use; third, to provide 20 a device of this class which may be quickly adjusted to suit the operator; fourth, to provide a device of this class which may be readily removed so that the accelerator may be operated with the ordinary pedal; 25 and fifth, to provide a device of this class which is very simple and economical of construction, durable, easy to operate, easy to install and remove, adjustable throughout 30 and which will not readily deteriorate or get out of order.

With these and other objects in view as will appear hereinafter my invention consists of certain novel features of construction, combination and arrangement of parts 35 and portions as will be hereinafter described in detail and particularly set forth in the appended claims, reference being had to the accompanying drawings and to the characters of reference thereon which form a 40 part of this application in which:

Figure 1 is a side elevational view of my device in operative position in connection with an accelerator pedal of one form and showing the footboard of the automobile 45 in section; Fig. 2 is a rear elevational view thereof; Fig. 3 is a sectional view through 3-3 of Fig. 1; Fig. 4 is a sectional view through 4-4 of Fig. 1; Fig. 5 is a similar view to that of Fig. 1 and showing the device 50 in operative connection with a different form of accelerator pedal; Fig. 6 is a similar view showing the device in operative position in connection with another form 55 of accelerator pedal and Fig. 7 is a perspective view of the same.

Similar characters of reference refer to

similar parts and portions throughout the several views of the drawings.

The supporting member 1 supporting member base 2, pedal engaging lever 3, 60 extension member 4 and adjusting bolt 5 constitute the principal parts and portions of my accelerator extension pedal.

The supporting member 1 is preferably an inverted U shaped member, one of the 65 members of which is preferably provided with flat sides and it is provided with a plurality of holes 1^a therein adapted to receive the cotter pin 3^a for supporting it in a pivotally mounted manner relative to 70 the supporting member 1. The other member of the supporting member 1 is preferably round and fits into a socket 2^a in the upper portion of the base member 2 and this base member 2 is provided with a set 75 screw 2^b adapted to rest against the inwardly extended end of member 1 and prevent it turning in said base member. This base member is provided with a flange 2^c with screws 2^d therein for securing it to 80 the footboard of the automobile. Pivotally mounted on the cotter pin 3^a is the accelerator pedal engaging member 3 by means of two oppositely disposed, integral extended portions 3^a which are provided with 85 holes adapted to receive said cotter pin and said pedal engaging member is provided with a portion extending normally backwardly and downwardly and provided with several angles adapting it to properly engage 90 the varying forms of accelerator pedals. The other extended main portion extends backwardly and slightly downwardly and is provided with an elongated hole 3^e therein in which is shiftably mounted an integral 95 lug 4^a on the one end of the member 4 which is extended at a right angle and may be inserted in said slot when the member 4 is in a position at a right angle to the member 3, then turned into alignment therewith. 100 This member 4 is provided with a threaded hole adapted for the adjusting screw 5 which sets up against the lower surface of the member 3^b and supports them in relative position to each other by frictional engagement of the members and they are further supported by the lug 4^a, thus providing for 105 the longitudinal shifting of the member 4 relatively to the member 3 and its adjustment thereon.

Though I have shown and described a particular construction, combination and ar-

rangement of parts and portions I do not wish to be limited to this particular construction, combination and arrangement but desire to include in the purview of my invention the construction, combination and arrangement substantially as set forth in the appended claims.

It is obvious that with this construction there is provided an accelerator extension 10 pedal in which the base member 2 may be positioned on the footboard as desired and the member 1 pivoted therein may be turned to any angle, that the member 3 is in bifurcated form the one member of which is 15 adapted to engage the conventional accelerator pedal and is so shaped that it is applicable for engagement with various makes of conventional accelerator pedals, that it is pivotedly mounted so that it may be adapted 20 to varying positions on the support 1 and that the other member is provided with an extension member, thus providing for the adjustment of the extension pedal to meet the varying requirements.

Having thus described my invention what I claim as new and desire to secure by Letters Patent, is:

1. An accelerator extension pedal, including a hinged support and an accelerator 30 engaging member pivotally mounted on the free side of said support and extending backwardly.

2. An accelerator extension pedal including a hinged support, an accelerator engaging member pivotally mounted on the free side of said support and extending backwardly and a pedal member, shiftable longitudinally thereon.

3. An accelerator extension pedal includ- 40 ing a hinged support, an accelerator en-

gaging member pivotally mounted on the free side of said support, a pedal member, shiftable longitudinally thereon and means for adjusting said pedal member relatively to said accelerator engaging member.

45

4. An accelerator extension pedal, including a hinged support, an accelerator engaging member pivotally mounted on the free side of said support, a pedal member, shiftable longitudinally thereon, and means for adjusting the position of said accelerator engaging member with the free side of said support.

50

5. An accelerator extension pedal, including a hinged support, an accelerator member pivotally mounted on the free side of said support, a pedal member, shiftable longitudinally thereon and means for adjusting said pedal member relatively to said accelerator engaging member.

55

6. A device of the class described, including a base member, an inverted U shaped support with one member pivotally mounted therein, means for holding it in certain position therein and an extensible accelerator pedal engaging member pivotally mounted on the free side of said support.

60

7. A device of the class described, including a base member, an inverted U shaped support with one member pivotally mounted therein, means for holding it in certain position therein, an extensible accelerator pedal engaging member pivotally mounted on the free side of said support and means for adjusting said pedal member relatively to said support.

70

In testimony whereof I have hereunto set my hand at San Diego, California, this 12th day of February, 1920.

FRED HARRINGTON.
